UNITED STATES PATENT OFFICE.

WILLIAM EVANS, OF PHILADELPHIA, PENNSYLVANIA.

IMPROVEMENT IN DUMPING-WAGONS.

Specification forming part of Letters Patent No. 222,392, dated December 9, 1879; application filed September 29, 1879.

To all whom it may concern:

Be it known that I, WILLIAM EVANS, of the city and county of Philadelphia, in the State of Pennsylvania, have invented a new and useful Improvement in Dumping-Wagons, of which the following is a specification.

My invention mainly consists in the combination of toothed sectors and pinions with the frame and body of a dumping-wagon in such a manner that by turning the crank-shaft of the pinions for operating the sectors, which are hinged or pivoted to the frame and body, the latter is brought into an inclined position for dumping its contents or discharging them by means of a chute, the position of the body being regulated by means of a roller and cords, or chains connected at one end with the roller and at the other end with the body.

In the accompanying drawings, which make a part of this specification, Figure 1 is a side elevation of a dumping-wagon with my improvements attached. Fig. 2 is a front elevation of the same. Fig. 3, Sheet No. 2, is a perspective view of the swinging gate M. Fig. 4 is a side view of one of the sectors C on an enlarged scale, in connection with one end of the rods E. Fig. 5 is an edge view of the same.

Like letters of reference in all the figures indicate the same parts.

A is the bed-frame of a wagon, and B the body.

C C are toothed sectors, which have hubs a, that are adapted to oscillate on bearings b b, which, in the present case, are the ends of the axle-bed D, the said ends being confined in the lugs e of the frame A.

The sectors at their periphery have lugs d, which have a permanent connection with the ends of the cross-rod E, which is adapted to turn freely in the lugs e e on the bottom of the body B.

G is a rotating shaft, having a crank, f. It has its bearings in lugs e' e' of the frame A, and is provided with pinions H H, and hence by turning the shaft in the direction of the arrow g the action of the pinions upon the sectors move them in the direction of the ar-

row h, whereby the body B is tilted into a position for dumping or discharging its contents through a chute into a cellar. The body is shown in the latter position in Fig. 1 by full lines, and in the former position by dotted lines. It is also shown in its closed position by dotted lines.

I have represented the sectors and pinions connected by means of spur-gearing; but, if desired, worm-gearing may be used instead of it.

The rear end of the body B beyond its pivotal connection with the sectors C C is purposely heavier than the front end, to cause it to tilt. The position is regulated by means of the roller I and cords or chains J J, one end of which is connected with the roller and the other end with the body. The roller is provided with the ratchet-wheel K.

L is a pawl which is hung to the frame A and connects with the ratchet-wheel.

By means of these devices, in combination with the sectors and pinions above described, the position of the body is regulated at any desired angle, or in an elevated horizontal position, the body being free to turn into either a horizontal or angular elevated position by means of its pivotal connection with the upper corners of the sectors C C, as above described.

Instead of the ratchet-wheel and pawl, a worm-wheel gearing or other device may be used for holding the roller I in its adjusted position.

M is a gate. (Shown in detail in Fig. 3.) It has an oscillatory connection with the rear end of the wagon by means of the pivots i i, whereby it is adapted to be used for the dumping operation; but in order that a coal-chute may be used when desired for discharging the contents of the wagon into a cellar, I provide the gate with the chute-mouth N, which has a sliding gate, O, for opening and closing it.

I claim as my invention—

1. The combination of the shaft G, having pinions H H and the sectors C C, with the frame A and body B, having lugs e e, the body being pivoted to the sectors by means of said

lugs and the cross-rod E, substantially in the manner and for the purpose set forth. FIGURE 2. The combination of the roller I and cords or chains J J with the frame A, body B, sectors C C, and pinions H H, for regulating the position of the body, the roller being held in its adjusted position by means of the

ratchet-wheel K and pawl L, or other convenient device, substantially as set forth.

WILLIAM EVANS.
